UNITED STATES PATENT OFFICE.

ANDRE SVEC, OF ASHLEY, PENNSYLVANIA.

TOY ROUNDABOUT.

1,379,486.

Specification of Letters Patent. Patented May 24, 1921.

Application filed November 9, 1920. Serial No. 422,888.

To all whom it may concern:

Be it known that I, ANDRE SVEC, a citizen of Czechoslovakia, residing at Ashley, in the county of Luzerne and State of Pennsylvania, have invented certain new and useful Improvements in Toy Roundabouts, of which the following is a specification.

This invention relates to certain new and useful improvements in toy roundabouts and has for one of its objects to provide a toy embodying a motor driven rotatable arm supporting carriages at the end thereof constructed in simulation of an airship.

A further object of the invention is to provide a mechanical toy having swingingly mounted carriages supported on a rotatable frame with a novel form of spring motor mechanism for rotating the frame.

With the above general objects in view and others that will appear as the nature of the invention is better understood, the same consists in the novel form, combination and arrangement of parts hereinafter more fully described, shown in the accompanying drawings and claimed.

In the drawings, wherein like reference characters indicate corresponding parts throughout the several views,

Figure 1 is a side elevational view of a toy constructed in accordance with the present invention,

Fig. 1^a is a top plan view of one of the swinging carriages carried by the toy, a portion of the supporting arm therefor being shown,

Fig. 2 is a horizontal sectional view taken through the central supporting standard of the toy showing the motor casing in top plan,

Fig. 3 is a cross sectional view taken on line III—III of Fig. 2 showing the motor operating mechanism for the power shaft,

Fig. 4 is a horizontal sectional view taken on line IV—IV of Fig. 3 showing the meshing gears and the spring motor for operating the same,

Fig. 5 is a cross sectional view taken through the motor casing showing the screw rod for adjusting the pinion for connecting and disconnecting the same with the spring gear,

Fig. 6 is a side elevational view, partly in section of the shiftable power transmission pinion with the supporting block therefor, and

Fig. 7 is a perspective view of the pinion.

Referring more in detail to the accompanying drawings and particularly to Fig. 1 there is illustrated a mechanical toy embodying a circular motor inclosing the casing 1 having a central bearing disk 2 supporting a vertical tubular casing 3 having spaced collars 4 at the upper end thereof between which the ring 5 of a transverse frame is rotatably mounted, said ring carrying oppositely disposed arms 6, while a flag staff 7 is supported above the tubular casing 3.

A carriage is carried by each outer end of the arms 6 and embodies a hanger 8 pivotally mounted at its upper end as at 9 within the bifurcated end of the arm 6, the carriage supported by the hanger including upper and lower rails 10 and 11 connected by vertical rods 12. A design toy in simulation of an aeroplane includes a body 13 supporting a rotatable propeller 14 at its forward end with a human figure 15 within the body 13 as clearly shown in Fig. 1.

A vertical power shaft 16 is journaled centrally within the tubular casing 3 with the lower end thereof supported in bearings 17 associated with the top wall 1' of the casing, the upper end thereof within the ring 4 of the transverse frame being suitably connected to the ring to effect rotary movement thereof. A gear wheel 18 is fixed to the lower end of the shaft 16 within the casing 1 and is in mesh with a shiftable pinion 19 supported by the top wall of the casing 1, the pinion in turn being in mesh with the spring driver gear 20. The spring driven gear includes a bearing shaft 21 extending upwardly through the top wall 1' of the casing while a band spring 22 has one end thereof secured as at 23 to the shaft 21, encircling the shaft with the outer free end thereof secured as at 24 to the outer side wall of the casing 1. The end of the shaft 21 projecting upwardly through the top wall 1' of the casing has a toothed wheel 25 secured thereto exteriorly of the casing with a finger piece 26 to effect rotation of the shaft 21 and the winding of the spring 22. When the shaft 21 is rotated to place the spring 22 under tension, the sliding dog 27 guided in the strap bearings 28 carried by the top wall 1' of the casing is moved to disengage the same from the toothed wheel 25 to permit free rotation of the shaft 21 and when proper tension has been placed on the spring, the dog 27 is reversely shifted.

to engage the wheel 25 and hold the spring under tension.

The shiftable pinion 19 is adapted to be moved to disengage the same from the gears 18 and 20 when the spring is placed under tension, and to accommodate such movement the pinion 19 is carried by the stub shaft 29, the latter being provided with a lateral flange 30 engaging the bottom face of the 10 casing cover 1' with the superposed block 31 projecting upwardly through the elongated slot 32 in the casing top. A shifting screw 33 has the opposite ends thereof rotatably mounted in bearings 34 carried by 15 the casing top 1' with the intermediate threaded portion thereof working through the threaded opening 31' in the block 31 while a finger piece 35 carried by one end of the screw 33 is provided for manipulating 20 the screw to shift the block 31. By rotating the screw 33, the block 31 and pinion 19 carried thereby is adapted to be moved at right angles to the alined gears 18 and 20 to engage and disengage the same from 25 said gears.

When the spring 22 is being placed under tension by rotation of the shaft 21 the pinion 19 is disengaged from the gears 18 and 20 so that the vertical shaft 16 will not be 30 rotated. The dog 27 maintains the spring 22 in a wound condition and when the pinion is shifted for engagement with said gears and the dog 27 again disengaged from the toothed wheel 25, the spring 22 will 35 rotate the shaft 21 supporting the gear 20 and communicate motion through the medium of the pinion 19 to the gear 18 carrying the shaft 16, thereby rotating the shaft and the transverse arms 6 connected to the 40 upper ends thereof with a circular swinging movement of the carriages suspended at the

outer ends of the arms. During such movement the propellers 14 carried by the figure aeroplanes 13 will be rotated to create the impression of flying machines.

45

While there is herein shown and described the preferred embodiment of the present invention, it is nevertheless to be understood that minor changes may be made therein without departing from the spirit and scope 50 of the invention as claimed.

What is claimed as new is:—

A toy of the type described comprising a casing, a vertical shaft rotatably supported therein, motor mechanism within the casing 55 for rotating the shaft, a cross arm supported on the upper end of the shaft and rotating therewith, a carriage swingingly mounted upon the outer ends of the cross arm, said motor mechanism including a train of gears 60 communicating with the rotatable shaft, one of said gears carrying a shaft extending upwardly through the casing, a spring connected at one of its ends to said shaft and at the other end to the inner wall of 65 the casing, means for placing the spring under tension, a toothed wheel carried by 70 said shaft above said casing, a sliding dog adapted to engage said toothed wheel to control rotation of the shaft, said casing having an elongated slot in the upper wall thereof, a block carried by one of said gears and extending upwardly through said slot, and an adjusting screw associated with said 75 block for shifting the block and gear carried thereby to disengage the same from the train of gearing whereby the rotatable shaft will remain stationary when the spring gear is being placed under tension.

In testimony whereof I affix my signature. 80

ANDRO SVEC.
